UNITED STATES PATENT OFFICE

163,999

VALVE HANDLE

Frederick H. Hehemann, Cincinnati, Ohio, assignor to The Lunkenheimer Company, Cincinnati, Ohio, a corporation of Ohio

Application April 14, 1951, Serial No. 14,837

Term of patent 14 years

(Cl. D78—1)

To all whom it may concern:

Be it known that I, Frederick H. Hehemann, a citizen of the United States, residing at Cincinnati, in the county of Hamilton, and State of Ohio, have invented a new, original, and ornamental Design for a Valve Handle, of which the following is a specification, reference being had to the accompanying drawing, forming a part thereof.

Figure 1 is a top plan view of the valve handle showing my new design.

Figure 2 is a side elevational view thereof.

I claim:

The ornamental design for a valve handle, substantially as shown.

FREDERICK H. HEHEMANN.
